UNITED STATES PATENT OFFICE

2,560,215

PROTECTION MASK AGAINST POISONOUS
GASES AND DUST

Marinus Christensen, Brorup, Denmark

Application December 5, 1946, Serial No. 714,207
In Denmark November 1, 1945Section 1. Public Law 690, August 8, 1946
Patent expires November 1, 1965

4 Claims. (Cl. 128—145)

1
This invention relates to protection masks against poisonous gases and dust.

By many kinds of work, such as spray-painting with cellulose enamels, the worker is in the risk of respirating poisonous gases and dust which gravely enthray his health. Several attempts have been made to overcome this inconvenience, such as providing the worker with a mask comprising a filter through which the respiration air is filtered so that the poisonous gases and dust are removed. Such mask, however, makes breathing difficult and is never wholly effective because the filter becomes successively obstructed and has to be cleaned or exchanged. It has also been attempted to exhaust the poisonous gases and dust from the place, where they are developed, by providing an exhausting duct, but such measures are only applicable in special cases; and they cannot be utilized by spraying apparatuses for poisonous liquids, the vapours from such liquids diffusing rapidly into the surrounding air which the worker must breathe. The said protection masks also have the drawback that they restrict the field of vision of the worker because he has to look through windows in the mask.

One object of this invention is to provide a protection mask for the purpose specified which does not require the use of a filter and which does not impede the breathing of the user.

Another object is to provide a protection mask which will give the user an unrestricted view, as if he wore no mask at all.

Still another object is to provide a protection mask which is very simple and inexpensive in manufacture, while still offering the user an effective and reliable protection against poisonous gases and dust.

A further object of the invention is to provide a mask for the purpose specified by means of which the user is constantly supplied with fresh air, free from contaminations.

Still another object is to provide a protection mask which allows the user to speak with his companions without the necessity of removing the mask.

The invention will be described in detail hereinafter, reference being had to the accompanying drawing, in which

Fig. 1 is a vertical sectional view of a mask in accordance with this invention,

Fig. 2 is a bottom plan view of the same, and

Fig. 3 illustrates how the mask is strapped to the user's cap or forehead.

Briefly spoken, the principle of the invention resides in that means are strapped or otherwise

2
secured to the forehead or cap of the user, by which a constant stream of fresh air is blown substantially vertically down in front the user's face so as to constitute an invisible curtain or screen around the same, and to scavenge the space around it. This "air jet screen" will, consequently, keep the surrounding air, which may be fouled with poisonous gases and/or dust, remote from the user's face.

10 In the embodiment illustrated in the drawing, the mask comprises an approximately semi-cylindrically bent plate 6 to which a cap-screen-shaped flange 7 is connected. Along the edge of the flange 7 there is an approximately vertical rim 8, and the plate 6 is at each end connected with a strap 9 or the like by means of which the mask can be secured to a cap of ordinary pattern.

The lower part 10 of the mask is likewise in 20 the form of a cap-screen and is provided with an upstanding flange 11 by means of which it is connected with the plate 6. Along its front edge the part 10 is provided with an upstanding rim 12, and between this rim and the rim 8 there is 25 formed an arcuate slot 13 extending to each side to a point 14 which, when the mask is in use, is situated adjacent the worker's ear, so that the air jet screen will inhibit any leaking-in of foul air at this place. The slot 13 may suitably 30 be of equal width over the whole of its length.

The lower part 10 is, at a place about 6 mm. behind the slot 13, provided with a tubular nozzle 15 which may conveniently be detachably secured so as to be capable of replacement with 35 another one of greater or smaller bore. The space 16 between the upper and lower parts of the mask is connected through a hose 17 with a compressor or other compressed-air supply from which compressed air is fed to the said 40 space so as to blow out, part through the slot 13 to constitute an air jet screen 18 surrounding the worker's face, and part through the nozzle 15 to constitute a separate air jet 19 directed towards the worker's nose and mouth behind the air jet screen 18. As shown in the drawing, a manually adjustable valve 22 is inserted in 45 the hose 17 at a suitable place thereof, by means of which valve the pressure within the chamber may be adjusted according to requirements.

50 In Fig. 3, the protection mask is shown strapped to a cap 20 on the head of a worker. The screen 21 of the cap is situated below the lower part 10 of the mask, but the slot 13 as well as the nozzle 15 are situated so far beyond the edge of 55 the cap screen that the air jets are not impeded

thereby. The cap screen will at the same time protect the worker's eyes against draft.

The mask may be made of metal, preferably aluminium or an aluminium alloy, or any other suitable material, such as plastics. The mask is inexpensive in manufacture, comfortable in use and affords absolute safety.

If the mask is made of castings it may be convenient to provide the upper part as well as the lower one with transverse partitions situated within the chamber 16 and bracing the two parts relative to each other.

In use it is recommendable to heat the compressed air conveniently in order to prevent excessive cooling of the user's face. For this purpose an electric heating member 23 may, for example, be mounted within the compressed-air chamber.

I claim:

1. A device for the protection against poisonous gases and dust comprising in combination a receptacle; means for securing said receptacle to a person's forehead; means for connecting said receptacle to a source of compressed air; jet means associated with said receptacle and extending in a continuous arcuate line around the wearer's face substantially from ear to ear and a nozzle arranged in the bottom of said receptacle within the concavity of said continuous arcuate line formed by said jet means, the said nozzle being directed toward the wearer's nose and mouth so as to pass an additional stream of air thereto.

2. A device for the protection against poisonous gases and dust comprising in combination a receptacle of a length and form to extend around a person's face substantially from ear to ear; means for securing said receptacle to the forehead of the wearer; means for connecting said receptacle to a source of compressed air; and a continuous arcuate slot provided in the bottom of said receptacle, the said slot being directed substantially parallel to the wearer's face so as to pass a transversely continuous stream of air downward and parallel to the wearer's face.

3. A device for the protection against poisonous gases and dust comprising in combination a receptacle of a length and form to extend around a person's face substantially from ear to ear;

means for securing said receptacle to the forehead of the wearer; means for connecting said receptacle to a source of compressed air; a continuous arcuate slot provided in the bottom of said receptacle, the said slot being directed substantially parallel to the wearer's face so as to pass a transversely continuous stream of air downward and parallel to the wearer's face; and a nozzle arranged in the bottom of said receptacle within the concavity of said arcuate slot, the said nozzle being directed toward the wearer's nose and mouth so as to pass an additional stream of air thereto.

4. A device for the protection against poisonous gases and dust comprising in combination a receptacle of a length and form to extend around a person's face substantially from ear to ear; means for securing said receptacle to the forehead of the wearer; means for connecting said receptacle to a source of compressed air; a continuous arcuate slot provided in the bottom of said receptacle, the said slot being directed substantially parallel to the wearer's face so as to pass a transversely continuous stream of air downward and parallel to the wearer's face; and a nozzle detachably arranged in the bottom of said receptacle within the concavity of said arcuate slot, the said nozzle being directed toward the wearer's nose and mouth so as to pass an additional stream of air thereto.
